DESIGN FOR AN AIRPLANE

Walter Tydon, East Aurora, and Lyle E. Parmely,
Buffalo, N. Y., assignors to Curtiss-Wright Cor-
poration, a corporation of Delaware

Application June 6, 1944, Serial No. 113,883

Term of patent 7 years

(Cl. D71—1)

To all whom it may concern:

Be it known that we, Walter Tydon and Lyle E. Parmely, citizens of the United States residing, respectively, in East Aurora and Buffalo, both in the county of Erie and State of New York, have invented a new, original, and ornamental Design for Airplanes, of which the following is a specification, reference being had to the accompanying drawing, forming a part thereof.

Figure 1 is a top plan view of an airplane showing our new design;

Figure 2 is a front elevational view;
Figure 3 is a side elevational view thereof; and
Figure 4 is a perspective view of the airplane
illustrating further details of our new design.

We claim:
The ornamental design for an airplane, as
shown.
